UNITED STATES PATENT OFFICE.

URBAN WELDON, OF COHOES, NEW YORK.

DYEING APPARATUS.

SPECIFICATION forming part of Letters Patent No. 380,838, dated April 10, 1883.

Application filed December 27, 1887. Serial No. 258,988. (No model.)

To all whom it may concern:

Be it known that I, URBAN WELDON, a resident of the city of Cohoes, in the county of Albany and State of New York, have invented 5 certain new and useful Improvements in Dyeing Apparatus; and I do hereby declare that the following is a full, clear, and exact description of the invention, that will enable others skilled in the art to which it appertains to make 10 and use the same, reference being had to the accompanying drawings, and to the letters of reference marked thereon, which form a part of this specification.

Similar letters refer to similar parts in the 15 several figures therein.

My invention relates to improvements in dyeing apparatus; and it consists of the novel construction and combination of parts herein-after described, and pointed out in the claims.

20 The invention is to be considered as an improvement upon the apparatus shown and described in United States Letters Patent No. 334,793, issued January 26, 1886, to A. Moran, to which reference may be had. The apparatus 25 therein described consisted, essentially, of a dipping wheel or cylinder rotary in a vat containing dye-stuff, and provided with perforated partitions for carrying the fabric through the dye-stuff, extending longitudinally 30 of the cylinder, and of a peculiar curved shape in cross-section, the curve extending in a long sweep from the hub on a point near the axle to the periphery of the wheel. This form of partitions caused the fabric to roll from a point 35 near the periphery of the wheel down to the hub as it was lifted from the dye-stuff, which more or less entangled and knotted the fabric, instead of imparting to it a half-revolution to bring its sides alternately in contact with the 40 carrying-partitions, the result being that the fabric was not dyed evenly.

To overcome the difficulty of rolling the goods, partitions having angular or V shaped pockets to receive the fabric have been employed; but this form does not wholly overcome the difficulty, as the inclination of the inner side wall of the V-shaped pockets thus formed in the partition near the periphery of the wheel causes the fabric to commence sliding or rolling therefrom before the pocket is vertically over the hub or axle of the wheel,

and as the wheel necessarily travels slowly the fabric will frequently be given a complete revolution in falling from the V-shaped pocket to the center of the wheel. I have ascertained 55 that by giving the partitions approximately the shape of a sickle, the part representing the handle of the sickle extending radially in an approximately straight line about half the distance from the hub to the periphery of the 60 wheel and the remaining distance in approximately the form of the blade of a sickle or semi-circle, the fabric will not start to leave the semicircular pockets until the radially-straight portion of the partition is nearly vertical, whereby only a semi-revolution is im- 65 parted to the fabric as it falls into the dye-stuff below, or upon the back of the contiguous pocket, which leaves it floating in the dye-stuff, to be again caught by the pocket which 70 has just dropped it, but with that side of the fabric which was previously in the bottom of the pocket now at the surface of the pocket, to be thoroughly permeated by the dye-stuff as the fabric is forcibly borne through it by 75 the moving pocket, the operation being repeated at each rotation of the wheel.

Another feature of my invention consists in forming the pockets of round rods extending longitudinally of the wheel to present only 80 rounded surfaces to the fabric and insure uniformity of surface throughout the length of the pocket, and thereby uniform treatment of the fabric.

Figure 1 of the drawings is a side elevation 85 of my improved apparatus. Fig. 2 is a central longitudinal section of my improved dipping wheel or cylinder. Fig. 3 is a vertical cross-section of the dipping-wheel detached. Fig. 4 is an end elevation of the apparatus shown 90 in Fig. 1. Figs. 5 and 6 are respectively longitudinal and transverse central vertical sections.

A represents the dipping-wheel, and B the vat containing the dye-stuff and adapted to receive the lower part of the wheel. The wheel is in the form of a cylinder made up of the two circular disks A', constituting the heads of the wheel or ends of the cylinder. These heads are connected by the longitudinal rods A², 95 forming the pockets a in the partitions b, and by a circular axle or hub, A³. The heads are 100

provided exteriorly with suitable gudgeons or bearings, A⁴, rotary in boxes A⁵, secured upon the end supports or heads of the vat. One of the gudgeons may have a pulley, A⁶, fixed thereon, or other means for receiving power.

The partitions b are made up of the round rods A², with spaces between, and the larger supporting-rod, a', all extending longitudinally of the wheel from head to head, and a series of short radial rods or slats, b', with small spaces between, the radial rods being supported at their outer ends by the longer longitudinal rod, A', and at their inner ends by 15 the hub A³. These partitions divide the wheel into spaces for receiving and carrying the fabric to be dyed, dipping it into the dye-stuff on one side of the vat, carrying it through the dye-stuff in the vat, and lifting it therefrom on 20 the opposite side of the vat and carrying it back, to be again dipped at each rotation of the wheel.

The vat is preferably made of the heads B', having a semicircular channel, F³, to receive 25 the ends of the staves F F', forming the bottom and sides of the vat, and held together by the threaded exterior rods, H, passing through the heads and secured by nuts B⁴, by which the heads are drawn tightly together, 30 the nuts and bolt-heads B³ resting upon the bearing-plates B². The central bottom stave, F', is made, preferably, thicker than the others, and provided with a longitudinal channel, F², adapted to receive the steam-pipe C, provided 35 with small escape-holes C', opening into the dye-stuff in the bottom of the vat for the purpose of heating it.

By having the steam-pipe countersunk in the bottom of the vat I am able to run the 40 wheel close to the bottom of the vat, and accomplish the operation of dyeing with a minimum quantity of dye-stuff.

By forming the partitions b entirely of rounded rods arranged with spaces between, 45 the dye-stuff is permitted to pass freely through the same, and the fabric cannot be cut or injured by contact with sharp edges.

By having the rods, forming the inner portion of the partitions, extend radially, the fab-

ric slides easily to or from the periphery of 50 the wheel, should it come in contact with the same in passing to and from the pockets a.

By having the pockets a semicircular in shape, substantially as shown, with the inner side wall of the pockets at their mouths about 55 right-angular to their respective radial partitions, of which they form an extension, I am able to repeatedly dip the fabric in the dye-stuff and reverse the position of the fabric in the pockets at each rotation of the wheel 60 without snarling or knotting it. By employing pockets the cross-sectional form of which is curved or rounded, instead of angular or V-shaped, the fabric is not liable to become wedged in the bottom of the pockets and be carried 65 around with the wheel without falling out, thereby securing a positive reversal of the position of the fabric relatively to the pockets at each rotation of the wheel, and consequent uniformity in distribution of dye stuff through 70 the fabric.

What I claim as new, and desire to secure by Letters Patent, is—

In a dyeing apparatus, a dipping wheel or cylinder rotary in a dye-vat, consisting of 75 two heads provided with bearings and connected by a hub, radial partitions, and longitudinal pockets, said partitions consisting of rows of pins or rods projecting radially from the hub to the several pockets at points about 80 half-way between the hub and periphery of the wheel, the pockets consisting of rounded rods extending longitudinally from head to head of the wheel, and having a cross-sectional arrangement approximately in the form 85 of a semicircle, the inside wall of the respective pockets at its point of junction with the rows of radially-projecting pins being approximately right-angular to said pins, substantially as described, and for the purposes 90 set forth.

In testimony whereof I have hereunto set my hand this 23d day of December, 1887.

URBAN WELDON.
